UNITED STATES PATENT OFFICE.

JOHN C. ROBESON, OF LOS ANGELES, CALIFORNIA.

GARMENT HANGER.

Application filed June 19, 1924. Serial No. 720,939.

To all whom it may concern:

Be it known that I, JOHN C. ROBESON, a citizen of the United States, residing at Los Angeles, in the county of Los Angeles, and State of California, have invented new and useful Improvements in Garment Hangers, of which the following is a specification.

This invention relates to garment hangers and consists of the novel features herein shown, described and claimed.

An object is to make a simple garment hanger adapted for supporting various garments.

Another object is to make a garment hanger having a main bar forming a primary garment support and having pivoted bars on top of the main bar and adapted to clamp a garment from the primary support and adapted to form secondary supports for other garments.

Other objects and advantages will appear from the drawings and specification.

The drawings illustrate the construction and use of a garment hanger embodying the principles of the invention.

Figure 1 is a view in elevation showing the construction and use of the garment hanger, parts being broken away and shown in section.

Fig. 2 is a top plan view as indicated by the arrow 2 in Fig. 1, the garment being omitted.

Fig. 3 is a cross sectional detail on the line 3-3 of Fig. 1.

Fig. 4 is a fragmentary perspective of the central portion of the hanger.

The details of construction and operation shown in the drawings are as follows:

The main supporting frame 1 is a curved bar. A hook 2 has a shank 3 extending downwardly through the center of the bar 1 with a washer 4 on its lower end under the bar and a head 5 against the washer. The supporting portions 6 and 7 of the bar 1 are the outer ends, as shown. Pads 8 and 9 are placed upon the upper edges of the portions 6 and 7. Coil springs 10 and 11 are mounted in seats at the inner ends of the portions 6 and 7 crosswise of the upper edges. Corresponding ends 12 and 13 of the springs extend along a side face of the bar and have hooks 14 and 15 extending across the lower edge of the bar and turned against the opposite face of the bar. Clamping members 16 and 17 have seats in their lower edges to fit

the coils 10 and 11 and the springs have arms 18 and 19 extending from the opposite ends from the arms 12 and 13 along the sides of the clamping members 16 and 17 and have hooks 20 and 21 extending over the edges and downwardly. The tension of the springs 10 and 11 are exerted to swing the outer ends of the clamping members 16 and 17 against the ends 6 and 7, and pads 22 and 23 are placed against the lower faces of the outer ends in opposition to the pads 8 and 9. The inner ends of the clamping members 16 and 17 have guide grooves 24 and 25 in which the shank 3 operates, and a sheet metal loop 26 extends around the center of the bar 1 and around the inner ends of the clamping members 16 and 17, the shank 3 extending through the loop and the loop serving to hold the inner ends of the members 16 and 17 in alinement. The upper edge 27 of the bar 1 is cut away to a straight line at the center of the bar and extending both ways from the shank 3 so that the inner ends of the clamping members 16 and 17 may be depressed to raise the outer ends to receive or release the garment 28.

The garment 28 is the upper part of a woman's apparel having a large neck, and the object is to place the shoulder portions 85 upon the supporting portions 6 and 7 and adjust the garment to the desired shape; then release the clamping members 16 and 17 to hold the garment in adjusted position.

If desired, a coat, jacket, or other garment 90 may be draped over the clamping members 16 and 17.

Thus I have produced a garment hanger comprising a main bar forming primary supports for a garment, pivoted bars on top of the main bar adapted to clamp the garment upon the primary supports, and adapted to form secondary supports for other garments.

Various changes may be made without departing from the spirit of the invention as claimed.

I claim:

A garment hanger comprising in combination a supporting frame in the form of a curved bar having its upper edge convex, a sheet metal loop secured to the frame at its mid position, the loop having a hole through the upper portion thereof, a hook having a shank passing through the hole in the loop and through the center portion of the frame, the hook being connected to the loop below

the bar, the said bar having its upper edge at the apex cut away at the center, a pair of clamping bars positioned over the supporting frame, the clamping bars and supporting bar having seats in their adjoining faces, coil springs mounted in said seats having their ends engaging respectively the clamping bars and the supporting frame

bar, the coils forming relatively stationary hinges for the clamping bars, the clamping bars being curved with the inner ends adapted to fit within the said loop.

In testimony whereof I have signed my name to this specification.

JOHN C. ROBESON.
